UNITED STATES PATENT OFFICE.

PETER L. MARKEY, OF CHICAGO, ILLINOIS.

NECKTIE HOLDER.

Application filed April 17, 1922. Serial No. 554,212.

To all whom it may concern:

Be it known that I, PETER L. MARKEY, a citizen of the United States, residing at Chicago, in the county of Cook and State of Illinois, have invented a new and useful Necktie Holder, of which the following is a specification:

My invention relates to a necktie holder and more particularly to a device which is adapted to support and hold up the tie in its proper position on the collar.

One of the objects of my invention is to provide an improved necktie holder on which the tie may be temporarily mounted or removed therefrom without the necessity of untangling the four-in-hand knot in the tie.

A further object is to provide a device which is adapted to hold the tie after the same has been tied on the collar up in proper position and thereby prevent the tie from falling below the collar button which usually gives the wearer a shiftless appearance. A further object is to provide a necktie holder which will occupy the least possible space between the folds of the collar.

These and other objects are obtained by providing a construction and arrangement of the various parts in the manner herein-after described and particularly pointed out in the appended claims.

Reference is to be had to the accompanying drawings forming a part of this specification in which similar figures or references indicate corresponding parts throughout the several views.

Referring to the drawings:

Fig. 1 is a side elevational view showing the manner in which my improved necktie holder supports a tie on a collar;

Fig. 2 is a cross sectional view taken on a horizontal plane passing through the collar button in Fig. 1;

Fig. 3 is a front elevational view of my improved necktie holder;

Fig. 4 is a cross sectional view taken on a vertical plane passing through the collar button in Fig. 1;

Fig. 5 is a front elevational view showing the manner in which the necktie holder may be utilized to support the tie in its proper position on the collar when the tie is positioned in the usual manner around the collar;

Fig. 6 is a top plan view showing the manner in which sharp points aggressively engage the necktie in supporting it in its proper position on the collar;

Fig. 7 is a front elevational view of a modified form of my necktie holder and

Fig. 8 is a side elevational view partly in section of Fig. 7.

In carrying out my invention, I employ a main base portion or support 1 which is preferably made of one piece of flexible metallic material. The base portion 1 is provided with a longitudinally extending slot 6 which is adapted to slidably receive a shank portion 13 of the collar button 14. Laterally extending and curved downwardly from the body portion 1 are arms 4. The outer end of the arms 4 have formed as a continuation thereof, vertically disposed prongs 5. These prongs 5 are so connected with the arms 4 as to form sockets 3 which are adapted to support that portion of the tie extending around the collar when the holder is employed to support the tie in the manner shown in Fig. 5. At the upper portions of the prongs 5 are laterally extending projections 16. These are normally employed to prevent the tie from slipping off the prongs 5 when mounted on the necktie holder as shown in Fig. 1. To increase the strength of the body portion 1 and to prevent the arms 4 from being distorted, I have provided an arch 10 formed integrally with the main body portion 1. This arch 10 is provided with an enlarged opening which is a continuation of the slot 6. This opening is adapted to receive the head of the collar button 14 as shown in Fig. 2. In order to take care of different heights of collars, I have provided means for relatively adjusting the necktie above the collar button on the collar. This means comprises a latch bar 7 provided with a series of notches on one edge thereof which are adapted to detachably engage a shank portion 13 of the collar button 14. The latch bar 7 is pivotally connected to the main portion 1 at the lower end thereof and is normally pressed into engagement with the collar button 14 by means of a spring 8. Spring 8 has one end connected to the body portion 1 and the other end thereof connected to the latch bar 7. The latch bar 7 is controlled or operated by a finger lever 15 formed integrally with and extending laterally from the latch bar 7. The arms 4 are provided on their top edges with upwardly projecting points 9 which are adapted to pierce the tie for supporting the same in its proper position on the collar.

These and other objects are obtained by providing a construction and arrangement of the various parts in the manner herein-after described and particularly pointed out in the appended claims.

Reference is to be had to the accompanying drawings forming a part of this specification in which similar figures or references indicate corresponding parts throughout the several views.

Referring to the drawings:

Fig. 1 is a side elevational view showing the manner in which my improved necktie holder supports a tie on a collar;

Fig. 2 is a cross sectional view taken on a horizontal plane passing through the collar button in Fig. 1;

Fig. 3 is a front elevational view of my improved necktie holder;

Fig. 4 is a cross sectional view taken on a vertical plane passing through the collar button in Fig. 1;

Fig. 5 is a front elevational view showing the manner in which the necktie holder may be utilized to support the tie in its proper position on the collar when the tie is positioned in the usual manner around the collar;

Fig. 6 is a top plan view showing the manner in which sharp points aggressively engage the necktie in supporting it in its proper position on the collar;

In order to fit collars of various sizes, I have provided a holder having a curvature to conform or to coincide with the curvature of a collar of the smallest size and when 5 the holder is used in connection with a considerably larger collar, the flexibility of the material of the holder is sufficient to conform the holder to the curvature of the larger collar.

- 10 In the operation of the above described device, it will be understood that the same is capable of use with the four-in-hand tie made in the usual way as shown in Fig. 5, that is, after the tie has been tied on the 15 collar in the usual manner my improved necktie holder is inserted beneath the knot of the tie with the collar button 14 passing down the slot 6 and the prongs 5 passing between the necktie 11 and the inner fold 20 12 of the collar. Then the points 9 aggressively engage the knot portion or the tie 11 until the tie is raised to the upper portion or proper position on the collar. The latch bar is then locked in the proper notch on 25 the collar button 13 and thus the tie is firmly supported in its proper position.

The better result, both in appearance to the wearer and in the life of the tie, is obtained by tying a four-in-hand tie by forming the tie 11 around the prongs 5 as shown 30 in Fig. 1. By doing this the tie may be removed from the necktie holder without untying the knot and another one substituted in its place. By this arrangement it 35 will be understood that a permanently formed tie will keep its shape and appearance considerably longer than a tie that is continuously being tied and untied.

In Figs. 7 and 8 the prongs 5 of the necktie holder are substantially in the same plane as the body portion of the necktie holder and additional inwardly projections 17 are provided. This modified form shown in 40 these two last mentioned figures may be employed in connection with soft collars. That is, the tie is formed about the necktie holder in substantially the same manner as above described and the points 17 may be employed 45 to engage the corners of the soft collars and hold them in their proper position.

While in the above specification I have de-

scribed but one embodiment which my invention may assume in practice, it will be understood however that the same is capable of modification, and that modification may be employed without departing from the spirit and scope of the invention as expressed in the following claims.

1. In a necktie holder, a base, curved arms extending laterally from said base, oppositely disposed prongs connected to said arms, means for detachably securing a tie to said prongs and means for adjustably securing said necktie holder on a collar. 60

2. In a necktie holder, a base, arms extending outwardly from said base, prongs formed integrally with said arms, a slot extending vertically in said base and an arch member extending across said slot for connecting said arms together. 65

3. In a necktie holder, a base, arms extending outwardly from said base, prongs connected to said arms and extending upwardly therefrom, and sockets formed between said arms and prongs for supporting 70 a tie in position on said holder.

4. In a necktie holder, a base having arms extending laterally therefrom, a plurality of prongs connected to the outer ends of said arms and positioned parallel with respect to each other, said base having a slot extending vertically therein, and an arched member formed integrally with said base having an enlarged opening forming a continuation of the slot in said base. 80

5. In a necktie holder, a base, arms extending upwardly from said base, prongs formed integrally with said arms, there being a slot extending vertically in said base, and a reinforcing member formed integrally with said base and extending from a point on said base adjacent the top of the slot thereof. 85

6. In a necktie holder, a base, curved arms extending outwardly from said base, there being a slot in said base, vertically disposed prongs formed integrally with and extending upwardly from said arms, and a reinforcing member formed integrally with said base and positioned adjacent said slot. 90

PETER L. MARKEY.
